UNITED STATES PATENT OFFICE

CHARLES SCHLAYER, OF NEW YORK, N. Y., ASSIGNOR OF ONE-HALF TO CHARLES W. JACOB, OF NEW YORK, N. Y.

CARBURETER.

1,207,224.

Specification of Letters Patent. Patented Dec. 5, 1916.

Application filed December 26, 1912. Serial No. 738,553.

To all whom it may concern:

Be it known that I, CHARLES SCHLAYER, a citizen of the United States, residing in the borough of Manhattan, in the city, county, and State of New York, have invented certain new and useful Improvements in Carbureters, of which the following is a specification, reference being had therein to the accompanying drawings, which form a part 10 thereof.

My invention relates to carbureters and more particularly to a type of suction carbureters.

The main object of the invention is to 15 provide a carbureter wherein the liquid hydrocarbon and air passing therethrough are brought into such intimate relation as to insure a thorough admixture thereof one with the other and any stratification of 20 either is prevented, thus insuring uniformity throughout practically the entire volume of the mixture delivered to the engine, or other point of consumption.

A further object is to provide a carbureter 25 wherein the volume of mixture delivered by the carbureter may be controlled, independently of the suction producing means, and the volume of air entering the carbureter will be simultaneously varied 30 in proportion to the volume of mixture being delivered.

A still further object is to provide a carbureter wherein air entering the carbureter will have imparted thereto a swirling motion 35 as it meets and first associates with, the vaporized liquid hydrocarbon, and the resulting mixture will be given a swirling motion, either as to the whole, or an effective portion of the volume thereof, to prevent 40 stratification of the vaporized hydrocarbon or air and secure a highly explosive mixture without an excess of the hydrocarbon, or globules thereof not combined with the proper volume of air, thus not only insuring 45 reasonable uniformity in the quality of the mixture, but economy in the operation of the carbureter and greater H. P. per gallon of fluid hydrocarbon.

A still further object is to provide a carbureter 50 wherein with an increased frequency of the suction impulses, and a re-

sultant proportionate lowering of the pressures within the mixing chambers and increase in the volume of vaporized hydrocarbon delivered to said chamber, supplemental 55 air delivery ports will become operative to increase the volume of air delivered to the mixing chamber, which air will be delivered in such manner and volume as to insure its combining with all portions of the mixture. 60

A still further object is to provide a carbureter wherein variance in the volume of liquid hydrocarbon delivered, will be determined by the effective suction applied at the delivery end of the spraying nozzle and variance in the volume of air will be controlled 65 in large measure by a mechanism controlled by the operator.

A still further object is to provide a carbureter wherein the mixture receives a sequence 70 of swirling motions while passing therethrough, the direction of succeeding motions being reversed to avoid any tendency of the formation of fixed courses for the hydrocarbon or air.

A still further object is to provide a carbureter wherein the float chamber may be readily detached from the mixing chamber, thus permitting repairs of said chamber without necessitating the disconnection of 80 the said mixing chamber.

A still further object is to provide a carbureter wherein a choke valve is provided for controlling the volume of the mixture delivered, the actuation of this valve causing 85 simultaneous actuation of the air intake controlling mechanism.

A still further object is to provide a carbureter wherein the valve controlling the delivery of the spraying nozzle may be set to 90 any desired capacity and the air intake controlling mechanism may be set to insure the delivery of a proportionate volume of air when any given suction is applied to the carbureter.

A still further object is to provide a carbureter wherein the main air intake duct will have an inlet of fixed capacity, be constricted adjacent the discharge of the spraying nozzle, and be capable of expansion beyond 100 its inlet to vary the capacity of the duct in proportion to the volume of mixture

being drawn from the carbureter, or the rate of flow of the mixture to the point of consumption.

A still further object is to provide a carbureter having a head flange which may be adjusted circumferentially of the mixing chamber, to permit the convenient adjustment of the carbureter to a manifold inlet head. And a still further object is to provide a carbureter for securing a thorough agitation and admixture of the liquid hydrocarbon and air wherein the agitating and mixing means will be so disposed as to avoid retardation of the flow of the mixture, and will not limit the capacity of the offtake or be subject to disarrangement or wear.

The invention consists in such novel features of construction and combination of parts as are hereinafter set forth and described, and more particularly pointed out in the claims hereto appended.

Referring to the drawings:—Figure 1 is a side elevation of a carbureter, embodying my invention; Fig. 2 is a similar view of the other side of the carbureter; Fig. 3 is a vertical section of a carbureter with the float chamber in elevation; Fig. 4 is a detail view of the air intake control mechanism; Fig. 5 is a detail view of the expanding air duct; Fig. 6 is a detail view of the auxiliary air intake ports and distributor; Fig. 7 is a top view of the auxiliary air intake section; Fig. 8 is a top view of the carbureter illustrating in dotted lines the adjustment of the head flange, and Fig. 9 is a detail view of the adjustable stop mechanism of the throttle control for controlling the minimum and maximum air capacity of the air intake mechanism. Fig. 10 is a detail view of the air damper.

Like letters refer to like parts throughout the several views.

Heretofore to secure a more thorough admixture of the hydrocarbon and air entering into an explosive mixture, it has been a common expedient to introduce a rotary member in the mixing chamber or in an engine manifold, which member was actuated by the flow of the mixture itself. This has proven more or less effective, but the constructions employed have always had the effect of retarding the flow to an extent determined by the dimensions and arrangement of this member. It has also been a common expedient to provide an auxiliary valve controlled air port for delivering a jet of air beyond the spraying nozzle which became operative when the engine was running at high speed. I have found, however, that the air delivered through this auxiliary port has a tendency to dilute only that portion of the mixture flowing across the discharge end of the port, thus failing to supply all cylinders of an engine with an explosive mixture having the same relative propor-

tions of hydrocarbon and air, thus resulting in a material loss of engine efficiency. Neither of the expedients above referred to have secured the results sought, that is a thorough admixture of the hydrocarbon and air, and a preservation of the desired proportions of such, irrespective of the rate of flow to the engine due to varying engine speeds.

By the herein described construction, I aim to secure a sufficiently thorough admixture of the hydrocarbon and air to admit of the close setting of the carbureter for determining the proportions of hydrocarbon and air, and preserving such proportions, or varying them to such an extent as to meet the requirements of the engine at different speeds.

In the embodiment of the invention shown in the drawings, I have shown a casing *a*, through which the hydrocarbon and air pass and are mixed. This casing is preferably cylindrical in cross section, and one open end thereof *a*¹ serves as an air intake port, and the other open end *a*² thereof serves as an explosive mixture offtake port, means as the head flange *a*³ being provided to facilitate the coupling of the carbureter to the engine manifold or a conduit leading thereto, (not shown).

Discharging within the casing *a*, is a spraying nozzle *b*, the discharge port of which is controlled by a needle valve *b*¹. Liquid hydrocarbon may be supplied said spraying nozzle in any desired manner, that shown and preferred being an ordinary float chamber *c* to which hydrocarbon is delivered through the supply pipe *c*'. That portion of the casing *a* adjacent the air intake port *a*¹, is constricted by means of a fitting *d* carrying a mixing tube or air duct to be more specifically referred to hereinafter. To vary the capacity of this tube or duct, I so construct it that it may be expanded or contracted according to the rate of flow of the explosive mixture from the carbureter, and provide means whereby it may be actuated to vary the air supply. Beyond the discharge end of the said tube or duct, I provide the inner wall of the casing *a* with a series of longitudinally extending helical or curved tongues *e* forming therebetween a series of similarly and laterally pitched channels, the purpose of which is to impart to the flowing mixture a swirling motion. Preferably I also provide a second series of such tongues *f* spaced away from the tongues *e* and being pitched reversely, thereto, both longitudinally and laterally thus tending to more thoroughly agitate and mix the hydrocarbon and air. The swirling motion will affect the entire volume of the mixture passing through the carbureter, and not only prevent any stratification, but permit such setting of the spraying nozzle and

air intake to secure a closer approximation of the proper proportions of hydrocarbon and air, with a resultant uniform richness of the mixture at any engine speed. To insure greater efficiency in mixing the hydrocarbon and air, I also provide the mixing tube or duct with similar helical or curved tongues thus causing the air to have a swirling motion when it first commingles with the hydrocarbon spray leaving the nozzle *b*. Mounted in a fixed relation to the casing *a* is an annular fitting *g* by means of which the mechanism for controlling the volume of air entering into the mixture is actuated.

To maintain as nearly as possible the proportion of hydrocarbon and air entering into the mixture at the higher engine speeds, I provide an auxiliary air intake comprising a series of ports *g'* in the fitting *g*, which ports are arranged circumferentially about and above the discharge end of the mixing tube or duct. These ports, to insure the rapid thorough admixture of the auxiliary air supply with the mixture flowing from said tube or duct, communicate with the interior of said casing through a series of helical or curved grooves or channels formed by the tongues *h*, the pitch of these tongues preferably being the reverse of that of the tongues within said tube or duct. The ports *g'* are opened and closed by a sliding gate *i*, the movement of which controls the capacity of the mixing tube or duct. Hence the delivery of the auxiliary air supply is timed to conform to the volume of air being delivered through the main air supply duct. The gate *i* has a series of longitudinal channels *i'* therein (see Fig. 4) preferably corresponding in number with the ports *g'*, the lower or intake end of these channels being open to atmosphere and the upper or discharge end being controlled by an annular valve plate *j*, which seats upon the top of said gate under the spring *j'* bearing upon a fixed shoulder within the casing *a*. A damper plate *j''* limits the intake of said channels *i'*. The fitting *d* is provided with an annular channel shown more particularly in Fig. 3, in which is seated one end of a plurality of overlapping shutters *k* constituting the mixing tube or duct hereinbefore referred to. These shutters each have a bearing which seats upon the edge of the channel, the shutters having a normal tendency to open under the tension of the coiled spring *k'* acting thereon below said bearing. The adjacent edges of the different shutters *k* are so constructed as to overlap when the tube or duct is set for its lowest capacity (see Figs. 4 and 5).

The fitting *g* is provided with an annular cam *l* adapted to engage the top of the shutters *k* and close them against the tension of the spring *k'* when the carburetor is set for a low rate of flow. This fitting is also

provided with a pendant flange *g''* for limiting the extent of expansion of the shutters *k* and defining the maximum capacity of the mixing tube or duct composed of said shutters *k*.

The fitting *d* and the gate *i* are so united as to be capable of simultaneous reciprocatory movement in the casing *a* by means of the throttle mechanism to be described.

Inasmuch as the volume of hydrocarbon delivered by the nozzle *b* will be determined by the pressure within the mixing chamber, and as with higher speeds, this pressure will be lower than with lower engine speeds, the capacity of this nozzle need not be varied to secure the desired proportions of hydrocarbon in the mixture at the higher speeds. Higher efficiency may be secured by allowing the volume of hydrocarbon to be determined solely by the changes in the pressures within the mixing chamber, the auxiliary air supply being utilized to dilute the mixture at the higher speeds, and equalize pressures, because of a tendency toward an excess of the hydrocarbon in the mixture. The stem *b'*, however, is made adjustable as shown, to permit the nozzle to be set when installing the carburetor.

Mounted in the casing *a* adjacent to the off-take *a'* thereof is a butterfly valve *m* adapted to control the rate of flow through and limit the capacity of the carburetor to the demands of the source of consumption. This valve is carried by a shaft *m'* projecting through the casing *a* and carrying at each end thereof an eccentric *n* adapted, with the actuation of said valve *m*, to actuate the expanding mixing tube or duct *k* and the gate *i* to vary the volume of air passing therethrough proportionately to the rate of flow determined by said valve *m*. Suitable connecting means between the said eccentrics *n* and the trunnions *i''* on the gate *i*, are provided, such means comprising the links *o*—*p*, one end of which respectively is mounted upon its trunnion, and the other end of which is provided with a laterally enlarged strap *o'*—*p'* adapted to be engaged by said eccentrics. Guide plates *o''*—*p''* mounted on said shaft hold said straps in the proper alignment. Suitable guide slots for the trunnions *i''* are provided in the casing *a*.

A crank arm *q* is mounted upon the shaft of the valve *m* and adapted to be connected with the throttle lever not shown. The spring *r* acting on the arm *r'* also carried by said valve shaft, acts to restore all parts to normal. The spring *s* acting upon either link *o*—*p* serves to hold both straps in engagement with their eccentrics. This last named spring acts against a seat *s'* on the casing *a* and a seat carried by its link.

To limit the minimum and maximum capacity of the off-take *a'* through the valve

m I provide the adjustable stops *t*—*t*¹ on the casing *a*, adapted to be engaged by the projection *t*² carried by the shaft of and movable with the valve *m*.

6 To afford a circumferential adjustment of the head flange *a*³, I make the tongues *f* in a cylinder *u* having a screw threaded connection with the casing *a*. This cylinder has a flange *u*¹ adapted to seat in a counter-sink in said head flange and force it against the annual shoulder *u*² upon the casing *a*.

Carried by the casing *a* is a downwardly opening keeper *v* adapted to receive a tongue *v*¹ on the tank *c* and be locked therein by 15 the bolt *v*², the nozzle *b* being supported by the elbow pipe *v*³ in order to permit the simultaneous removal of the float tank *c* and nozzle *b* for purposes of cleaning or repair.

The operation of the herein described carbureter is substantially as follows: The needle valve *b* and the stops *t*—*t*¹ are first adjusted to secure the proper relative minimum quantities of hydrocarbon and air entering into the mixture. This may be readily accomplished as the needle valve *b*' has its end exposed below the casing *a*, and the said stops are arranged exteriorly of said casing. When in operation the automatic variance of the pressure about and beyond 25 the discharge end of the spraying nozzle controlled by the rate of flow of the mixture from the mixing chamber as determined by the rate of consumption of the mixture, will simultaneously vary the volume of air drawn through the mixing tube or duct *k*, the auxiliary air supply becoming operative only when the maximum capacity of the said tube does not admit a volume of air proportionate to the volume of hydrocarbon issuing 30 in the form of spray from the said nozzle *b*. After setting the valve *b*' and stops *t*—*t*¹, the carbureter should be brought to its greatest capacity and the damper plate *j* set to define the maximum capacity of the channels *i*¹ to insure the delivery of the proper volume of air with the actuation of the auxiliary air supply system. By thus adjusting the carbureter, the proportion of hydrocarbon is determined solely by the rate of flow 35 of the mixture, or the pressure within the carbureter which is determined in part by the engine speed and in part by the valve *m*.

When in operation at low engine speeds, the lever *q* is actuated to simultaneously 45 turn the valve *m* to reduce the volume of mixture passing from the off-take *a*² and through the links *o*—*p*, to raise the fitting *d* and gate *i*. This will force the top of the shutter *k* into engagement with the cam *l* to contract the tube to its lowest 50 capacity, and cause the gate *i* to close the auxiliary air ports, *g*'. While the intake capacity of the mixing tube or duct remains constant each shutter *k* as to its inner face is curved as shown, so as to have

the smallest diameter of the tube adjacent to the nozzle *b*, both ends thereof gradually flaring outwardly as shown in Fig. 3. With the carbureter thus set the air passing through the said tube or duct will be directed toward the axis of the casing *a*, the tongues *k*² forming channels about the inner face of said tube imparting a swirling motion to practically the entire volume of air passing therethrough by reason of their longitudinal spiral trend. The lateral pitch 70 of the channels between these tongues results in their being of gradually decreasing depth and aids in imparting to the entire volume of air this swirling motion through 80 the lateral direction of the air current. That reduction in pressure within the upper portion which results in the setting up of the current of air through the mixing tube, simultaneously, and in the usual manner, 85 causes the liquid hydrocarbon to be sprayed from the nozzle *b* so as to be commingled with the incoming air. This mixture after leaving the mixing tube is expanded into the mixing chamber and passes within the ring 90 of tongues *e*, from which it receives a swirling motion in a direction opposite to that imparted thereto by means of the tongues *k*², a portion of the mixture being directed toward the axis of the casing *a* by the lateral 95 pitch of the bottoms of the channels between the said tongues *e*. This swirling motion and the cross currents, serve to thoroughly mix the hydrocarbon spray and air and at the same time avoid any possibility of a 100 stratification of either. The valve *m*, by limiting the capacity of the mixing chamber adjacent thereto, will correspondingly vary the volume of mixture passing through the off-take *a*² and hence control the rate of 105 flow and the pressure within the mixing chamber, which in turn will determine the proportions of hydrocarbon and air entering into the mixture. That portion of the mixture passing through the off-take *a*², receives a final swirl from the tongues *f*, the lateral pitch of the channels between which will set up cross currents toward the axis of the casing *a* in the manner heretofore referred to in connection with the tongues *k*² and *e*, the direction of the swirling motion, however, being the reverse of that developed 110 by the tongues *e*.

Inasmuch as the spray leaving the nozzle *b* has a swirling motion due to the rapid impulses to which the mixture in the mixing chamber is subjected, the hydrocarbon and the air, and the mixture thereof, will be constantly agitated in passing through the carbureter. This will insure a sufficiently thorough admixture of the hydrocarbon and air to insure a highly explosive mixture, and by preventing an excess of hydrocarbon in any part of the mixture, permit a closer approximation in the setting of the spraying 125 130

nozzle to secure the proper proportion thereof entering into the mixture. This not only effects a saving of hydrocarbon, but higher engine efficiency is secured as all 5 cylinders will receive a mixture of substantially the same richness. With the swirling action, the reversal thereof and the development of cross currents stratification is practically impossible.

- 10 When increased capacity is demanded, the valve *m* is opened to the desired extent, thus increasing the rate of flow, with a proportionate reduction of pressure within the mixing chamber and a consequent proportionate increase of the flow of hydrocarbon and air from the nozzle *b*, and through the mixing tube or duct, respectively. Simultaneously with the opening of the valve *m* the eccentric *n* on its shaft *m'* will, 15 through the straps *o'-p'* and links *o-p* lower the gate *i* and the mixing tube or duct. With this movement the tops of the shutters *h* will be forced outwardly by the spring *h'*, the cam *l* defining the extent of 20 this opening. Hence the capacity of the said mixing tube will be increased although its intake capacity remains constant. At the same time, the movement of the gate *i* will open the ports *g'* proportionately to the 25 extent of movement of the gate and throttle valve. This merely results in a proportionate increase of hydrocarbon and air in a volume determined by the rate of consumption or flow of the mixture.
- 30 35 If the valve *m*, gate *i* and the mixing tube be adjusted to their maximum capacity, as when an engine is running at high speed, the reduction of pressure within the mixing chamber will be so great that the air required will be in excess of the capacity of 40 the mixing tube. Under such conditions the valve plate *j* will be unseated against the tension of its spring *j'* and thus simultaneously deliver air to the mixture leaving the 45 mixing tube or duct, at all points about the wall of the mixing chamber. The air passing through the ports *g'* is delivered into the mixing chamber through the channels formed by the tongues *h*, the longitudinal and lateral pitch of these channels causing a swirling motion and cross currents similar to 50 those caused by the tongues *e*, *f* and *h²*. This manner of delivering the auxiliary air supply not only insures the dilution of the 55 mixture, but prevents the dilution of only that portion thereof adjacent to the point of delivery of the auxiliary air supply. This delivery of the auxiliary air supply at a number of points about the mixing chamber preserves the uniform dilution of the 60 mixture, and causes each cylinder of an engine running at high speed to receive a mixture of the same richness. The lever *r'* and spring *r* have a normal tendency to open the 65 valve *m*.

By the construction herein described a continuous agitation of the hydrocarbon and air, and the mixture thereof, is secured without obstructing the mixing chamber or reducing the effective capacity of the carbureter. The agitation is secured without the aid of moving parts, and the action is continuous. There may be a variance in the velocity of the flow through the unobstructed central portion of the casing *a* and of the 70 flow adjacent said casing, but with the swirling of the mixture, a tendency toward such would be minimized although any such variance would merely tend to accentuate the cross currents and aid in securing the desired thorough admixture of the hydrocarbon and air.

When helical or curved tongues are used about the wall of the casing, there is little or no tendency toward condensation of the 80 hydrocarbon, or the removal of the heavier particles of hydrocarbon through centrifugal action.

The adjustment of the head flange *a³* and the removal of the float chamber may be 90 readily accomplished and will permit the attachment of the carbureter to manifolds or pipes, without material changes, or the removal of the float tank and spraying nozzle without disturbing the remaining portions of the carbureter.

It is not my intention to limit the invention to the details of construction shown in the drawings, it being apparent that such may be varied without departing from the 100 spirit and scope of the invention.

Having described the invention, what I claim as new and desire to have protected by Letters Patent is:—

1. A carbureter embodying therein a 105 spraying nozzle, means delivering liquid hydrocarbon thereto, a mixing chamber having an offtake port leading therefrom, an air intake communicating therewith, means adjacent the wall of said chamber and the 110 discharge end of said air intake whereby the mixture has a whirling motion in one direction imparted thereto, and means adjacent said offtake arranged adjacent the walls of said chamber, whereby said mixture has a whirling motion in the opposite direction imparted thereto, the central portion of said chamber being unobstructed by said means.

2. A carbureter embodying therein a 120 spraying nozzle, means delivering liquid hydrocarbon thereto, a mixing chamber having an offtake port leading therefrom, an air intake communicating therewith, a plurality of helical or curved tongues adjacent 125 the wall of said chamber and the discharge end of said air intake, whereby the mixture has a swirling motion in one direction imparted thereto, and a plurality of helical or curved tongues adjacent the wall of said 130

chamber and within the said offtake, said last named tongues being pitched reversely to said first named tongue whereby the mixture has a swirling motion in the opposite direction imparted thereto, the central portion of said chamber being unobstructed by said tongues.

3. A carbureter embodying therein a spraying nozzle, means delivering liquid hydrocarbon thereto, a mixing chamber having an offtake port leading therefrom, a mixing tube surrounding said nozzle, means whereby said tube may be expanded and contracted to vary the volume of air delivered to said mixing chamber, and means carried by said tube whereby a swirling motion is imparted to the air passing therethrough.

4. A carbureter embodying therein a mixing tube comprising a plurality of movable shutters, pivotally supported adjacent the intake end thereof, a spring acting thereon having a normal tendency to separate the other end thereof, a cam adapted to engage and close said shutters against the tension of said spring, and means whereby the relative position of said shutters and said cam may be varied to control the capacity of said tube.

5. A carbureter embodying therein a spraying nozzle having a discharge port of fixed capacity, a mixing chamber having an offtake port leading therefrom, an adjustable valve controlling the rate of flow of the mixture through said mixing chamber and the pressure about said nozzle, a reciprocatory, expansible mixing tube having a fixed intake capacity, means adapted with the reciprocation of said tube to vary its capacity adjacent said nozzle whereby the volume of air passing through said tube and the pressure about said nozzle may be simultaneously and inversely varied to cause a proportionate increase or decrease in the volume of air and hydrocarbon entering said mixing chamber, and connections between said valve and said tube whereby they are simultaneously actuated to proportion the capacity of said tube to the rate of flow of the mixture.

6. A carbureter embodying therein a spraying nozzle having a discharge port of fixed capacity, a mixing chamber having an offtake port leading therefrom, a rotary valve within said mixing chamber controlling the rate of flow of the mixture through said mixing chamber and the pressure about said nozzle, a reciprocatory, expansible mixing tube having a fixed intake capacity, means adapted with the reciprocation of said tube to vary its capacity adjacent to said nozzle whereby the volume of air passing through said tube and the pressure about said nozzle may be simultaneously and inversely varied to cause a proportionate increase or decrease in the volume of air and

hydrocarbon entering the mixing chamber, reciprocatory links, connections between said links and said tube, and an eccentric and strap connection between said links respectively, and the shaft of said rotary valve, whereby said valve and said tube will be simultaneously actuated to proportion the capacity of said tube to the rate of flow of the mixture.

7. A carbureter embodying therein a spraying nozzle having a discharge port of fixed capacity, a mixing chamber having an offtake port leading therefrom, a rotary valve within said mixing chamber controlling the rate of flow of the mixture through said mixing chamber and the pressure about said nozzle, a reciprocatory, expansible mixing tube having a fixed intake capacity, means adapted with the reciprocation of said tube to vary its capacity adjacent to said nozzle whereby the volume of air passing through said tube and the pressure about said nozzle may be simultaneously and inversely varied to cause a proportionate increase or decrease in the volume of air and hydrocarbon entering the mixing chamber, reciprocatory links, connections between said links and said tube, eccentric and strap connections between said links respectively, and the shaft of said rotary valve whereby said valve and said tube will be simultaneously actuated to proportion the capacity of said tube to the rate of flow of the mixture, adjustable stops and a projection carried by the shaft of said valve whereby the maximum or minimum adjustment of said valve and said tube may be regulated.

8. A carbureter embodying therein a spraying nozzle having a discharge port of fixed capacity, a mixing chamber having an offtake port leading therefrom, means controlling the rate of flow of the mixture through said offtake port and the pressure about said nozzle, a mixing tube surrounding said nozzle having a fixed intake capacity, means varying the capacity of said tube adjacent the discharge port of said nozzle whereby the volume of air passing through said tube and the pressure about said nozzle may be inversely varied to cause a proportionate increase or decrease in the volume of air and hydrocarbon entering said mixing chamber, and means whereby an auxiliary air supply may be discharged into said mixing chamber to preserve the proportions of air and hydrocarbon entering said chamber, comprising a port opening into said chamber adjacent to the discharge end of said mixing tube, a gate normally closing said port and having air ducts therein, and an automatically acting valve controlling said ducts.

9. A carbureter embodying therein a spraying nozzle having a discharge port of fixed capacity, a mixing chamber having

- an offtake port leading therefrom, an adjustable valve controlling the rate of flow of the mixture through said mixing chamber and the pressure about said nozzle, a reciprocatory, expansible mixing tube having a fixed intake capacity, means adapted with the reciprocation of said tube to vary its capacity adjacent said nozzle whereby the volume of air passing through said tube and the pressure about said nozzle may be simultaneously and inversely varied to cause a proportionate increase or decrease in the volume of air and hydrocarbon entering said mixing chamber, connections between said valve and said tube whereby they are simultaneously actuated to proportion the capacity of said tube to the rate of flow of the mixture, and means whereby an auxiliary air supply may be discharged into said mixing chamber to preserve the proportions of air and hydrocarbon entering said chamber, comprising a port opening into said chamber adjacent to the discharge end of said mixing tube, a gate carried by and reciprocating with said tube normally closing said port and having air ducts therein, and an automatically acting valve controlling said ports.
10. A carbureter embodying therein a spraying nozzle having a discharge port of fixed capacity, a mixing chamber having an offtake port leading therefrom, an adjustable valve controlling the rate of flow of the mixture through said mixing chamber and the pressure about said nozzle, a reciprocatory, expansible mixing tube having a fixed intake capacity, means adapted with the reciprocation of said tube to vary its capacity adjacent said nozzle whereby the volume of air passing through said tube and the pressure about said nozzle may be simultaneously and inversely varied to cause a proportionate increase or decrease in the volume of air and hydrocarbon entering said mixing chamber, connections between said valve and said tube whereby they are simultaneously actuated to proportion the capacity of said tube to the rate of flow of the mixture, and means whereby an auxiliary air supply may be discharged into said mixing chamber to preserve the proportions of air and hydrocarbon entering said chamber, comprising a port opening into said chamber adjacent to the discharge end of said mixing tube, a gate carried by and reciprocating with said tube normally closing said port and having air ducts therein, an automatically acting valve controlling said ports and an adjustable damper adapted to regulate the intake capacity of said ducts.
11. A carbureter embodying therein a spraying nozzle, a mixing chamber into which said nozzle discharges, a mixing tube delivering air about said nozzle, and auxiliary air supply means including therein a plurality of ports divergently arranged about the wall of said mixing chamber, a reciprocating gate having a plurality of air channels therein each adapted to deliver air to one of said ports, an annular valve plate, a spring acting thereon to normally seat same to close said channels, and means adapted to simultaneously vary the capacity of said mixing tube and reciprocate said gate to bring said valve plate into operative position.
12. A carbureter embodying therein a spraying nozzle, a mixing chamber into which said nozzle discharges, a mixing tube delivering air about said nozzle, and auxiliary air supply means including therein a plurality of ports divergently arranged about the wall of said mixing chamber, a reciprocating gate having a plurality of air channels therein, each adapted to deliver air to one of said ports, an annular valve plate, a spring acting thereon to normally seat same to close said channels, means adapted to simultaneously vary the capacity of said mixing tube and reciprocate said gate to bring said valve plate into operative position, and an adjustable damper plate controlling the inlet to said channels.
13. A carbureter embodying therein a spraying nozzle, means delivering liquid hydrocarbon thereto, a mixing chamber having an offtake port leading therefrom, an air intake communicating therewith, means adjacent the wall of said chamber whereby the central portion of said chamber is unobstructed and the mixture passing through said chamber has a swirling motion imparted thereto, and auxiliary air supply means including therein a plurality of ports arranged divergently about the wall of said mixing chamber, a series of helical or curved tongues forming channels between said ports and said mixing chamber, means whereby each of said ports is in communication with a source of air supply, and means simultaneously controlling the flow of air through all of said ports.
14. A carbureter embodying therein a spraying nozzle, means delivering liquid hydrocarbon thereto, a mixing chamber having an offtake port leading therefrom, an air intake communicating therewith, means adjacent the wall of said chamber and the discharge end of said air intake whereby the mixture has a swirling motion in one direction imparted thereto, means adjacent said offtake arranged adjacent the walls of said chamber whereby said mixture has a swirling motion in the opposite direction imparted thereto, the central portion of said chamber being unobstructed by said means, and auxiliary air supply means including therein a plurality of ports divergently arranged about the wall of said mixing chamber.

ber, a series of helical or curved tongues forming channels between said ports and said mixing chamber, means whereby each of said ports is in communication with a 5 source of air supply, and means simultaneously controlling the flow of air through all of said ports.

15. A carbureter embodying therein a spraying nozzle, means delivering hydro- 10 carbon thereto, a mixing chamber having an offtake leading therefrom, a mixing tube surrounding said nozzle, means adjacent the wall of said mixing tube whereby a swirling motion in one direction is imparted to 15 the air passing therethrough, means adjacent the wall of said chamber and the discharge end of said mixing tube whereby a swirling motion in the opposite direction is imparted to the mixture passing through 20 said chamber, and auxiliary air supply means including therein a plurality of divergently arranged ports about the wall of said chamber, means imparting a swirling motion to the air passing through said ports, 25 the direction of which motion is the reverse

of that imparted by said mixing tube, means whereby each of said ports is in communication with a source of air supply, and means simultaneously controlling the flow of air through all of said ports. 20

16. A carbureter embodying therein a mixing tube, and agitating means comprising a plurality of longitudinally extending helical tongues arranged about the axis of 35 said tube and forming a series of channels adjacent the wall thereof, the bottom of said channels being pitched axially and inwardly of said tube in the direction of the flow of the mixture therethrough whereby a swirling motion is imparted to the gaseous matter flowing adjacent the said tongues and lateral or cross-currents are set up within 40 said tube.

In witness whereof I have hereunto affixed my signature this 21st day of December, 1912, before two witnesses. 45

CHARLES SCHLAYER.
